UNITED STATES PATENT OFFICE.

CHARLES L. BOWMAN, OF BOWDIL, OHIO.

CLUTCH-SHIFTING DEVICE.

Application filed November 8, 1922. Serial No. 599,696.

To all whom it may concern:

Be it known that I, CHARLES L. BOWMAN, a citizen of the United States, residing at Bowdil, in the county of Stark and State 5 of Ohio, have invented certain new and useful Improvements in Clutch-Shifting Devices, of which the following is a specification.

This invention relates to devices for shifting 10 clutches and has for its object the provision of a simple and inexpensive device which may be readily applied to any machine and by which the clutch may be easily thrown in or out and be positively 15 held in either position. In the operation of various machinery, it is frequently necessary or advisable to quickly throw in or out the clutch by which a shaft is connected to a driving member, and the devices here- 20 tofore provided for this purpose are objectionable for the reason that they do not firmly hold the clutch in the position in which it may be set so that it will slip in or out prematurely and when such action is 25 not desired. The object of the present invention is to provide a device which will overcome this objection, and such a device is illustrated in the accompanying drawing. The invention resides in certain novel fea- 30 tures which will be hereinafter first fully described and then more particularly pointed out in the appended claims.

In the drawing:

Figure 1 is a side elevation of my im- 35 proved device showing it in the position assumed when the clutch is thrown out;

Fig. 2 is a similar view showing the de- 40 vice in the position assumed when the clutch is in, and

Fig. 3 is an end elevation with the shaft in transverse section.

The reference numeral 1 in the drawing denotes a fixed part of any machine which is to be operated. A bracket 2 which may 45 be of any preferred or convenient form is secured rigidly upon the fixed member 1, and this bracket is provided with a depend- 50 ing hanger member 3 at its free end. Ful- crumed upon the hanger 3 adjacent the up- 55 per end thereof is a hand lever 4 which has its lower end reduced in thickness or offset, as shown at 5, and provided with a longi- tudinal slot 6. A pivot bolt 7 is inserted through the slot 6 and through the bifur- 60 cated or forked upper end of a shifting 65 yoke or rocking arm 8, the forked or bi-

furcated end 9 of the shank of the rock- 60 ing arm or yoke receiving the reduced or offset extremity 5 of the hand lever, as clearly shown. The rocking arm is pivot- 65 ally mounted upon the lower extremity of the hanger 3 by a pivot bolt 10 and the lower extremity of said rocking arm is formed into a fork or yoke 11 adapted to engage in an annular groove 12 in the 70 clutch member 13 which is splined upon the shaft 14. The clutch member 13 may be of any well-known form and co-operates with a mating clutch member 15 which is secured rigidly to the driving pulley or 75 gear. Upon one side of the fork or yoke 11 is an upwardly projecting elongated eye or link 16 in which is engaged the lower ex- 80 tremity 17 of a coiled spring 18, the upper end of which is engaged over a headed stud or bolt 19 on the hand lever 4 above the fulcrum of the same. To facilitate a smooth action of the parts in shifting the clutch member 13, the edge portions of the fork 11 are tapered, as indicated at 20, so that 85 the fork may rock easily upon the opposed walls of the groove 12.

It will be readily noted that the fulcrum or pivot of the hand levers and the fulcrum or pivot of the rocking arm are substantially 90 in vertical alinement, while the lower end of the spring is attached to the fork below the lower pivot and the upper end of the spring is attached to the hand lever above 95 the pivot of the same. When it is desired to 100 shift the clutch, the hand lever 4 is merely rocked to one side upon its pivot and the rocking arm will be rocked in the opposite direction through the connection of the up- 105 per end thereof to the lower end of the hand lever, the slot 6 accommodating the varying angular relation of the pivot 7 to the end of the hand lever. As the lever is rocked in either direction, the upper end of the spring will, of course, be carried there- 110 with and the tension of the spring will be somewhat increased, but as soon as the stud 19 passes beyond a position vertically over the pivot of the hand lever, the spring will contract and exert a pull through the eye or loop 16 upon the fork 11 which will resist retrograde movement of the fork. Conse- 115 quently, the spring will permit the clutch to be quickly and easily shifted in either direction whenever desired but will hold the clutch in the position in which it may be set. The tension of the spring serves to

throw the joint between the hand lever and the rocking arm beyond the dead center in both directions and the clutch will be effectually held in a set position without the use of racks, pawls or similar devices. It will be readily noted that the terminals of the spring are at right angles to each other to permit proper engagement with the stud 19 and the eye or link 16 and that they may slide readily upon the stud and the link, respectively, to accommodate the varying relation of the parts and the shifting of the line of pull or tension. My improved device is exceedingly simple and compact and may be readily applied to clutches in any position upon any machine.

Having thus described the invention, what is claimed as new is:

1. The combination with a slidable clutch member, of a rocking arm engaging said member, a transverse elongated eye upon one side of said arm below the pivot of the same, a lever mounted above the rocking arm, a pin and slot connection between the lower end of the lever and the upper end of the rocking arm, and a contractile spring having its lower end engaged in the said transverse elongated eye and its upper end engaged with the lever above the fulcrum of the same.
2. A clutch-shifting device comprising a clutching member shifting yoke provided with a shank having a bifurcated free terminal, a hanger support, a shifting lever having an offset lower end extended between the furcations of said shank, a lost motion pivot connection between said offset lower end and said shank, means for pivotally connecting said shank to said support, means for pivotally connecting said lever above its offset lower end to said support, a headed

stud projecting laterally from said lever above its offset lower end, a link projecting upwardly from said yoke, and a resilient element slidably connected to said 45 stud and link.

3. A clutch-shafting device comprising a clutching member shifting yoke provided with a shank having a bifurcated free terminal, a hanger support, a shifting lever having an offset lower end extended between the furcations of said shank, a lost motion pivot connection between said offset lower end and said shank, means for pivotally connecting said shank to said support, means for pivotally connecting said lever above its offset lower end to said support, a resilient connection having hook-shaped ends, said hook-shaped ends extending at right angles with respect to each other, means for slidably connecting one of said hook-shaped ends to said lever, and means for slidably connecting the other of said hook-shaped ends to said yoke.

4. A clutch-shifting device comprising a clutching member shifting element, a hanger support, a shifting lever having an offset lower end extending into said element, a lost motion pivotal connection between said offset end and said element, means for pivotally connecting said element to said support, means for pivotally connecting said lever to said support, a vertically disposed resilient element, means for slidably connecting one end of said resilient element to said lever, and means for slidably connecting the other end of said resilient element to said shifting element.

In testimony whereof I affix my signature.

CHARLES L. BOWMAN. [L. S.]
